UNITED STATES PATENT OFFICE.

HENRY CUTLER, OF NORTH WILBRAHAM, ASSIGNOR TO HIMSELF, GEORGE E. CUTLER, C. F. CUTLER, AND B. T. THOMPSON, OF SOUTH FRAMINGHAM, MASSACHUSETTS.

STEAM GRAIN-DRIER.

SPECIFICATION forming part of Letters Patent No. 247,818, dated September 20, 1881.

Application filed May 27, 1881. (Model.)

To all whom it may concern:

Be it known that I, HENRY CUTLER, of North Wilbraham, in the county of Hampden and State of Massachusetts, have invented certain useful Improvements in Steam Grain-Driers, of which the following is a specification.

Figure 1 is a sectional side elevation of my improvement. Fig. 2 is a sectional end elevation of the same, taken through the line xx , Fig. 1. Fig. 3 is an end elevation of the same, part being broken away. Fig. 4 is a side elevation of the same, part being broken away.

Similar letters of reference indicate corresponding parts.

The object of this invention is to improve the construction of the steam grain-drier for which a patent was allowed to me December 13, 1880, in such a manner as to make it more convenient in use and more effective in operation.

The invention consists in constructing the end spider with curved arm and a conical flange to receive the grain, and holes to receive the steam-pipes; also, in the combination, with the casing and the discharge-trough, of the jacket and its suspending-bands, whereby the grain will be prevented from escaping through the ventilating-apertures when the said apertures are turned to the lower part of the drier; also, in the combination, with the trough provided with an opening and the jacket, of the casing J, provided with the buckets over the discharge-openings of the casing; also, in the combination, with the hollow head, the spiders, and steam-pipes, of the auxiliary steam-pipes; also, in constructing the journal of the drier-shaft with a central passage, to admit steam, and side passages, to discharge the water of condensation; also, in the combination, with the drier-shaft having side passages through its journal, of the stationary sleeve having interior groove and the pipe to receive and carry off the discharge-water; also, in constructing the hollow head of the drier with lifting-buckets and outlet-pipes, which communicate with the outside passages of the drier-shaft; and, also, in the combination, with the drier-shaft having side passages and

the hollow head, of the outlet-pipes, the stationary grooved sleeve, and the pipes that receive and carry off the discharge-water, all as will be hereinafter fully described.

A is a shaft, placed in a slightly-inclined position and revolving in bearings in suitable supports.

To the shaft A, at a little distance from the lower bearings, is attached a head, B, which is made hollow to receive steam and distribute the steam to the pipes C. The forward ends 60 of the pipes C are screwed into the inner side of the head B, near its rim. The pipes C, at their other ends, pass through holes in the rim of a spider, D, the hub of which is attached to the shaft A. The outer or rear ends of the 65 pipes C are connected in pairs by return-bends E, as shown in Figs. 1 and 4, to induce a circulation of steam through the said pipes. The arms of the spider D are curved outward, as shown in Fig. 1, and upon the rim of the said 70 spider, at or near its inner edge, is formed, or to it is attached, a conical flange, F. The flange F and the concavity of the outer side of the spider D form a recess or space to receive the grain, which is introduced through a spout, G, 75 from some convenient receptacle. The steam-head B, the pipes C, and the spider D form a drying-cylinder, which can be made of any desired length, as the amount of drying to be done may require.

One, two, or more spiders, H, to support the pipes C, can be placed upon the shaft A, between the head B and the spider D, as the length of the cylinder may require. The pipes C can cross the rims of the spiders H and be 85 secured to the said rims in pairs by straps passing over the pairs of pipes, and having their ends secured to the said rims by screws or other suitable fastenings; or the pipes C can be passed through holes in the rims of the said spiders H. An increase of heating-surface can be obtained from another set of pipes, I, placed around and at a little distance from the shaft A, and the forward ends of which are screwed into the inner side of the steam-head B. The pipes I pass through holes in the middle parts or arms of the spiders H, and are connected in pairs at the outer side of the last spider H

- by return-bends I', as shown in Figs. 1 and 4. The pipe-cylinder is inclosed by a casing of boards, J, which rest upon hoops K, placed around the pipes C. The ends of the casing-boards J are placed beneath the flanges or lips L, formed upon the inner edges of the steam-head B and the end spider, D. The casing-boards J are further secured in place by hoops M, placed around them, as shown in Fig. 1.
- 10 Any desired number of inner hoops, K, and outer hoops, M, can be used, as the length of the drier may require.
- In the casing J, near the lower end of the drier, are formed a number of slots or apertures, 15 N, through which the moisture expelled from the grain can escape. The grain is kept from escaping through the apertures N when the revolution of the drier brings the said apertures downward by a semi-cylindrical jacket, 20 O, which surrounds the lower part of the casing J, and is held against the said casing by bands P, passed over said casing and attached to the edges of the said jacket O. The jacket O is held stationary by being attached at its 25 lower edge to the edge of the discharge-trough Q, which is supported by some suitable means beneath the lower part of the drier. The upper edges of the trough Q are concaved to fit upon the lower side of the cylindrical casing 30 J. In the bottom, side, or end of the trough Q is formed an aperture, R, through which the dried grain escapes to some suitable receiver.
- To the casing-boards J, over the discharge-openings in the said casing, are attached buckets S, opening to the rearward, which become filled with grain when the said discharge-openings are downward, and discharge their contents into the trough Q as the said discharge-apertures rise. With this construction, as the 35 drier revolves the grain passes over and around the drying-pipes, gradually passes down in a spiral direction toward the lower end of the drier, and is discharged into the trough Q.
- In the forward end of the shaft A is formed 40 a longitudinal perforation, T, from which cross-perforations U open into the interior of the head B, so that steam can be introduced into the said head without interfering with the rotation of the drier.
- To the inner surface of the outer side of the 45 head B are attached, or upon it are formed, plates or buckets V, to raise the water of condensation from the lower part of the interior of the said head and cause it to flow out through the pipes W, the outer ends of which are secured in apertures in the outer side of the said head, at a little distance from its rim. The inner ends of the pipes W are connected with the inner ends of the passages X, which pass 50 longitudinally through the outer part of the shaft A and open at their outer ends into the ring-groove in the inner surface of the sleeve Y, through which the shaft A passes, and

which is made to fit the said shaft A water-tight by packing or stuffing boxes. 65

To the sleeve Y is attached the end of the pipe Z, which opens into the ring-groove of the said sleeve, and through which the water of condensation passes off to some suitable receiver. The pipe Z holds the sleeve Y stationary, while the shaft A revolves within the said sleeve. 70

The drier can be revolved by steam or other power applied to the shaft A by a belt and pulleys or other suitable means. 75

Having thus fully described my invention, I claim as new and desire to secure by Letters Patent—

1. In a steam grain-drier, the end spider, D, constructed, substantially as herein shown and 80 described, with curved arms and a conical flange to receive the grain and holes to receive the steam-pipes, as set forth.

2. In a steam grain-drier, the combination, 85 with the casing J and the discharge-trough Q, of the jacket O and the suspending-bands P, substantially as herein shown and described, whereby the ventilating-apertures in the lower part of the casing J are covered and the escape of grain through the said apertures is prevented, as set forth.

3. In a steam grain-drier, the combination, 90 with the trough Q, provided with the opening R and jacket O, of the casing J, provided with the buckets S over the discharge-openings of the said casing, as and for the purpose set forth.

4. In a steam grain-drier, the combination, 95 with the hollow head B, the spiders D H, and steam-pipes C C', of the auxiliary steam-pipes I I', substantially as and for the purpose set forth.

5. In a steam grain-drier, the journal of the shaft A, made with a central passage, T, to admit steam, and side passages, X, to discharge the water of condensation, substantially as 100 herein shown and described.

6. In a steam grain-drier, the combination, 105 with the shaft A, having side passages, X, through its journal, of the stationary sleeve Y, having interior groove and the pipe Z, substantially as herein shown and described, to receive and carry off the discharge-water, as set forth.

7. In a steam grain-drier, the hollow head B, provided with the lifting-buckets V and the outlet-pipes W, which communicate with the 110 outside passages, X, of the shaft A, substantially as and for the purpose set forth.

8. In a steam grain-drier, the combination, 115 with the shaft A, having side passages, X, and the hollow head B, of the pipes W, the stationary grooved sleeve Y, and the pipe Z, substantially as and for the purpose set forth.

HENRY CUTLER.
